(57) **CLAIM**

I claim the ornamental design for an electronic device, as shown and described.

DESCRIPTION

FIG. 1 is a front perspective view of an electronic device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged cross-sectional view taken through line 9-9 of FIG. 2;

FIG. 10 is a front perspective view of another embodiment of an electronic device showing my new design;

FIG. 11 is a front view of FIG. 10;

FIG. 12 is a rear view of FIG. 10;

FIG. 13 is a left-side view of FIG. 10;

FIG. 14 is a right-side view of FIG. 10;

FIG. 15 is a top view of FIG. 10;

FIG. 16 is a bottom view of FIG. 10; and,

FIG. 17 is a rear perspective view of FIG. 10.

The dash-dash broken lines in the figures show portions of the electronic device which form no part of the claimed design.

The dot-dash broken lines in the figures represent the bounds of the claimed design and form no part of the claimed design.

1 Claim, 17 Drawing Sheets
